Meyers, Cushing & Rea
ATTORNEY

UNITED STATES PATENT OFFICE.

HUGO SCHNEIDER, OF NEW YORK, N. Y.

TOILET ARTICLE.

1,339,673.

Specification of Letters Patent. Patented May 11, 1920.

Application filed May 23, 1919. Serial No. 299,299.

To all whom it may concern:

Be it known that I, HUGO SCHNEIDER, a citizen of Germany, (having obtained first papers for citizenship of the United States,) 5 residing at New York, in the county of New York and State of New York, have invented new and useful Improvements in Toilet Articles, of which the following is a specification.

10 This invention relates to certain new and useful improvements in the manufacture of toilet articles such as mirrors, brushes, buffers, polishers and the like, and while I have in the present instance shown the invention as applicable to a mirror, it will of course be understood that it is not limited to this particular article.

In the present instance it is my purpose to provide a toilet article wherein the body 20 portion is composed of united sections or shells of suitable material, such as celluloid, having the resultant hollow or space therebetween filled or packed with a plastic material, preferably in the nature of a composition which will permanently possess a certain degree of plasticity, so that the article in its complete form will have inherent therein the desired features of solidity and weight, coupled with strength and 25 durability.

Furthermore, in the construction of my article, I am enabled to employ a relatively light, inexpensive material for making the shells or sections of the body portion, and 30 I preferably use celluloid for this purpose, inasmuch as this substance may be easily molded, worked or shaped to any desired form, and readily ornamented to suit the individual taste or requirement. The plastic 35 composition employed as the filler may be placed in position either before or after the shells or sections have been assembled, and the use of such filler will not only impart the desired solidity, weight and 40 rigidity to the article body, but will also prevent warping and eliminate labor in the insertion or placement of glasses and the like, in addition to accomplishing a great 45 saving, in some instances as high as seventy-five per cent., in the amount of the relatively expensive material usually employed 50 in forming the body portion of articles of this class.

Another object of the invention is to 55 avoid the loosening, cracking, shrinking and breaking up of the filler which would occur

under the wear and tear incident to use were the filler made of a material which will harden and set to rigid form with the elapse of time. By making the filler of a 60 material or composition which permanently retains a degree of plasticity, I obviate these disadvantages of a rigid filler, and prolong the life and utility of the article. 65

With the above recited objects and others 70 of a similar nature in view, my invention consists in the construction, combination and arrangement of parts set forth in and falling within the scope of the appended claims:

In the accompanying drawing:

Figure 1 is a perspective view of one-half of a shell or section intended to constitute the front part of the body portion of a 75 mirror.

Fig. 2 is a similar view of one-half of a shell or section intended to form the back part of the body portion of the mirror.

Fig. 3 is a longitudinal sectional view taken through the assembled shells or sections prior to the insertion of the filling. 80

Fig. 4 is a longitudinal sectional view taken through the finished mirror.

Fig. 5 is a perspective view of the mirror 85 on a reduced scale.

Referring now to the accompanying drawing in detail, the letter A indicates the shell or section which is to form the front of the body portion of the article, while the letter B designates the shell or section for 90 the back. These two shells may be made of any suitable material, such as metal, wood, composition or the like, but I prefer to employ celluloid for this purpose, as it possesses manifest advantages from sanitary, 95 manufacturing and ornamental standpoints. The front shell A is dished to provide the depression 1, the circumscribing wall of which is formed by the U-shaped flange 2. The handle portion of this shell A is shown 100 at 3, and is formed with a single depending flange 4. This front shell is preferably molded from a single sheet of celluloid, and is formed with an opening 5, for the purpose hereinafter set forth. The back shell 105 B is also preferably molded from a single shell of celluloid, and is provided with a single, continuous, up-standing flange 6. These two shells are adapted and intended to be assembled one on the other, as shown 110 in Fig. 3, with the back shell telescoping in the front shell so that an enlarged hollow or

space is formed between the enlarged sections of the shells and in communication with the hollow or space formed by the handle section 3 of the front shell and the handle section 7 of the back shell. After the two shells have been so assembled and have been permanently united or secured together at their flange portions through the use of a suitable medium, such as acetone, the filler C is poured or fed through the opening 5 in a sufficient quantity to completely fill the space or hollow between the shells, as will be understood by reference to Fig. 4. This filler C is preferably in the nature of a waxy composition which will permanently retain a certain degree of plasticity when cooled, but which may be heated to assume a fluid state so that it may be readily poured through the opening 5. In one of its forms this filler is composed of wax, marble-dust and rosin, but I do not limit myself to these particular ingredients, as any substance or composition which may be brought to a fluid-like condition at one stage and which will subsequently assume a waxy, plastic state without hardening and setting will answer the purpose. After this filler has been inserted, as shown in Fig. 4, the article may be finished by trimming or cutting and then buffing and polishing along the meeting edges of the flanges, as will be understood by a comparison of Figs. 3 and 4. In positioning or placing the glass of the mirror, a soft pad or cushion of cotton or other suitable material may first be laid in the depressed or dished section 1, and the glass 9 then imposed on this pad and held in position by means of a binding ring 10, of celluloid, or any other and preferred material. The complete mirror will then appear as shown in Fig. 5.

While I have herein shown and described one preferred embodiment of my invention I wish it to be understood that I do not confine myself to all the precise details of construction herein set forth by way of illustration, as modification and variation may be made without departing from the spirit of the invention or exceeding the scope of the appended claims. For example, instead of making the shell sections of celluloid, they may be of metal or thin sheets of wood,

or of mineral or other compositions, and the filler may be placed in position before the two sections have been united as well as 55 thereafter.

What I claim is:

1. In a toilet article of the class described, a plurality of celluloid shells united at their edges to form a hollow body portion, and a 60 filler therefor comprising a plastic composition sufficiently yieldable under normal conditions to substantially prevent cracking and breaking thereof.

2. In a mirror, a hollow body portion 65 provided with a depression having a filling opening, a composition filler located in the hollow body portion, said filler being permanently yieldable and capable of withstanding and absorbing shocks or blows 70 without cracking or breaking, and a mirror glass located in said depression and overlying the said opening.

3. In an article of the class described, a front shell section composed of celluloid and 75 having a dished portion and a handle portion, a back shell section composed of celluloid and having an enlarged portion united with the dished portion of the front shell section and a handle portion united with 80 the handle portion of said front shell section, the united sections forming a hollow body, a mirror glass secured in said dished portion of the front section, and a filler formed of a plastic composition occupying 85 the space within the hollow body portion, said filler being sufficiently yieldable under normal conditions to withstand shocks or blows without cracking or breaking thereof.

4. In an article of the class described, a 90 plurality of opposed sections marginally connected to form a hollow body portion, one of said sections being provided with a filling opening and a filler of plastic material adapted to be poured through said opening to fill said hollow body portion and form a solid filler therefor, said plastic material being sufficiently yieldable under normal conditions to substantially prevent cracking and breaking thereof. 95

In testimony whereof I have hereunto set my hand.

HUGO SCHNEIDER.
